(57) **CLAIM**

The ornamental design for a suction cup holder for a cellular telephone, as shown and described.

DESCRIPTION

FIG. 1 is a front perspective view of a suction cup holder for a cellular telephone showing my new design;

FIG. 2 is another front perspective view thereof;

FIG. 3 is a front elevational view thereof;

FIG. 4 is a rear elevational view thereof;

FIG. 5 is side view thereof;

FIG. 6 is another side view thereof;

FIG. 7 is a top plan view thereof;

FIG. 8 is a bottom plan view thereof;

FIG. 9 is a rear perspective view thereof; and,

FIG. 10 is another rear perspective view thereof.

The broken line showing of the cellular telephone and vehicle dashboard in FIGS. 1 and 9 is for illustrative purposes only and forms no part of the claimed design.
